NEEDLE CLAMPING DEVICE FOR SEWING MACHINES

Charles F. Rubel, Chicago, Ill., assignor to Union Special Machine Company, Chicago, Ill., a corporation of Illinois

Application December 1, 1933, Serial No. 700,589

2 Claims. (Cl. 112—226)

The present invention relates to improvements in devices for clamping the needle of a sewing machine to the needle bar, and more particularly to an improved needle clamping device which consists of a minimum number of parts; which is inexpensive to manufacture, easy to assemble and extremely durable.

An object of the present invention is to provide an improved needle clamping device wherein a collar member carrying a single set-screw is adapted to be placed on the lower end of the needle bar and wherein the set-screw is adapted to hold a needle in position and to support the collar in position against an abutment on the needle bar whereby no additional securing member is necessary so that the assembly consists of a minimum number of parts.

The above and other objects of the invention will in part be obvious and will be hereinafter 20 more fully pointed out.

In the drawing:

Figure 1 is an elevation showing the assembled needle and needle clamping device on a needle bar.

Fig. 2 is a side view of Fig. 1.

Fig. 3 is a view, similar to Fig. 1, but partly in section to show the arrangement of the various parts and the details of construction.

Fig. 4 is a sectional view taken along the line 4—4 of Fig. 1.

Fig. 5 is a view taken along the line 5—5 of Fig. 3.

Referring to the accompanying drawing, there is illustrated a needle bar 10, which is adapted to reciprocate within the head of a sewing machine (not shown) in the usual manner. The needle bar 10 is provided, at the lower end thereof, with a reduced end portion 11, thereby affording a horizontal shoulder or abutment 12, which extends around the needle bar at the point where the reduced portion 11 joins the body portion thereof. The reduced end portion 11 is provided with a vertical recess 13 which communicates with a horizontal recess 14 which extends laterally into the needle bar to a point slightly beyond the central axis thereof. The horizontal axis of the recess 14 is substantially in line with the horizontal abutment 12 on the needle bar 10. Intermediate the ends of the reduced portion 11, there is provided an opening 15 which extends through the annular wall of the reduced portion 11 and thus communicates with the vertical recess 13 therein. A collar member 16 is adapted to fit over the reduced end 11 of the needle bar

with the upper surface thereof engaging the horizontal shoulder 12. This collar carries an integral depending arm 17 which has a laterally extending portion 18. The laterally extending portion 18 has an opening 19 with which a slot 20 communicates whereby to form a substantially forked end on the portion 18. A set screw 21 is adapted to extend through a hole in the collar 16 and to threadedly engage the same. The screw 21 is provided with a reduced end portion 22 which is adapted to pass through the opening 15 in the wall of the reduced end 11 of the needle bar 10. It will thus be apparent that the shoulder abutment 12 on the needle bar 10 serves as a means for properly positioning the collar 16 on the end 11 of the needle bar 10 so that when the collar is fitted thereon, the end 22 of the screw 21 will be in exact alignment with the opening 15 in the needle bar. A needle 23 is then inserted through the opening 19 in the laterally extending portion 18 with the shank 23a thereof passing through the vertical recess 13 in the lower end of the needle bar. The screw 21 is then turned so that the end 22 thereof will pass through the opening 15 and engage the shank 23a of the needle 23 and thus clamp the same firmly against the opposite portion of the wall of the reduced end 11 of the needle bar and at the same time clamp the opposite face of the collar 16 against the end 11. The reduced end 22 of the screw 21 in the opening 15 will prevent the collar 16 from descending on the needle bar so that the entire assembly is held on by a single screw 21 which also serves to hold the needle 23 in place. The laterally extending portion 18 of the arm 17 serves as a thread guide. The thread is passed through the slot 20 so that it will be led from the take-up mechanism to a point in close proximity to the shank of the needle and thence down to the eye of the needle. The upper end of the needle shank 23a is curved and fits snugly against the curved surface of the opening 14. It is difficult to drill the vertical recess 13 to an exact depth within close limits to provide a bearing surface for the upper end of the needle and it is for this reason that there is provided the horizontal recess 14 which intersects the vertical recess. Thus, it will be noted that the upper surface of the recess 14 affords a stop whereby the needle 23 may be inserted into the needle bar 10 to a fixed depth and also affords an accurate bearing surface for the end 23a thereof.

It will be noted, from the foregoing descrip-

tion, that an extremely simple and efficient device for clamping the needle of a sewing machine to the needle bar is herewith provided. The device consists of a few parts so that they 5 may be of rugged construction. Relatively coarse threads may be employed in the screw and collar in order to increase the strength and durability of the device since there is no threaded engagement of the screw with the needle bar. The shoulder 12 serves as a convenient means for positioning the collar on the needle bar so that the small end of the screw will pass through the opening 15 to clamp the needle.

It is to be clearly understood that minor 15 changes may be made in the details of construction and arrangement of parts without departing from the scope of the invention as set forth in the appended claims.

What I claim as new and desire to secure by 20 Letters Patent, is:—

1. The combination with a needle bar having a reduced end portion, a vertical recess extending upwardly through said reduced end portion, a horizontal shoulder around the needle bar at 25 the point where the reduced end portion thereof joins the body portion thereof, a horizontal recess extending laterally into said needle bar and intersecting said vertical recess, and an opening through the wall of said reduced end 30 portion, of a needle having the shank thereof inserted in said vertical recess with the upper end bearing against the surface of said horizontal recess, of a collar member having a threaded horizontal recess, said collar member being 35 adapted to be fitted over said reduced end portion with the upper face thereof abutting against said shoulder whereby to position the threaded recess therein in axial alignment with the opening in the wall of said reduced end portion, and of a screw member adapted to threadedly engage the threaded recess in said collar member and having a reduced end adapted to extend through the opening in the wall of the reduced end portion of the needle bar whereby to clamp the needle and the collar member in position.

the opening in the wall of said reduced end portion, and of a screw member adapted to threadedly engage the threaded recess in said collar member and having a reduced end adapted to extend through the opening in the wall of the 5 reduced end portion of the needle bar whereby to clamp the needle and the collar member in position.

2. The combination with a needle bar having a reduced end portion, a vertical recess extending upwardly through said reduced end portion, a horizontal shoulder around the needle bar at the point where the reduced end portion thereof joins the body portion thereof, a horizontal recess extending laterally into said needle bar 10 and intersecting said vertical recess, and an opening through the wall of said reduced end portion, of a needle having the shank thereof inserted in said vertical recess with the upper end bearing against the surface of said horizontal recess, of a collar member having a threaded 15 horizontal recess, and an integral thread guide depending therefrom and encircling the needle whereby to lead the thread in close proximity to the shank of the needle, said 20 collar member being adapted to be fitted over said reduced end portion with the upper face thereof abutting against said shoulder whereby to position the threaded recess therein in axial alignment with the opening in the wall of said 25 reduced end portion, and of a screw member adapted to threadedly engage the threaded recess in said collar member and having a reduced end adapted to extend through the opening in the wall of the reduced end portion of the needle 30 bar whereby to clamp the needle and the collar member in position.

CHARLES F. RUBEL.
